CLAIM

The ornamental design for a gun-mounted telescoping support stand apparatus as shown and described.

DESCRIPTION

FIG. 1 is a detailed top rear perspective view of a gun-mounted telescoping support stand apparatus in accordance with my new design;

FIG. 2 is a detailed top front perspective view thereof;

FIG. 3 is a rear view thereof;

FIG. 4 is a front view thereof;

FIG. 5 is a left view thereof;

FIG. 6 is a right view thereof;

FIG. 7 is a top view thereof;

FIG. 8 is a bottom view thereof; and,

FIG. 9 is a top rear perspective view of the gun-mounted telescoping support stand apparatus with the legs shown in an open configuration.

The broken lines having equal dash lengths in the drawings illustrate portions of the gun-mounted telescoping stand apparatus that form no part of the claimed design. The dash-dot-dash lines indicate boundaries of the claimed design and form no part thereof. The solid line brackets in FIG. 9 identify symbolic break lines that form no part of the claimed design. The areas between the symbolic break lines form no part thereof.

1 Claim, 9 Drawing Sheets
